UNITED STATES PATENT OFFICE.

JOHN FRANCIS MURPHY, OF LOUISVILLE, KENTUCKY.

INTERNAL-COMBUSTION ENGINE.

1,222,657.

Specification of Letters Patent. Patented Apr. 17, 1917.

Application filed November 16, 1915. Serial No. 61,807

To all whom it may concern:

Be it known that I, JOHN F. MURPHY, a citizen of the United States, residing at Louisville, in the county of Jefferson and State of Kentucky, have invented certain new and useful Improvements in Internal-Combustion Engines, of which the following is a specification.

This invention relates to internal combustion engines, and more particularly to a novel improvement in engines of that type having a variable compression chamber.

As is well known, in the ordinary type of internal combustion engine, there is an untraveled space in the end of the cylinder known as the compression or combustion chamber. At the end of the working cycle, this chamber is filled with products of combustion, and the incoming charge of fuel 20 is diluted by it to such an extent that at low throttle, the carburetor must be adjusted to give a very rich mixture. This dilution of the combustible charge by the inert gases remaining in the cylinder not only causes a loss of efficiency, but makes the motor less sensitive to adjustment, because there is a variable proportion of active and dead gases for every speed.

Accordingly, the present invention has 30 primarily in view a construction whereby the spent gases and products of combustion are completely removed at the end of each working stroke of the piston, thereby providing for the free and full reception of a 35 fresh live charge at the beginning of the suction stroke, which is free from dead gases and therefore of maximum efficiency.

Another object of the invention is to provide a novel and practical arrangement of 40 parts whereby the above object may be effectively carried out with silence of operation, and positive and accurately synchronized movements.

A further object is to provide a simple adjusting device whereby the valve action 45 may be advanced with relation to the crank shaft, while the engine is running, for extreme speeds, so as to counteract as much as possible the inertia of the gases.

With the above and other objects in view 50 which will more readily appear as the nature of the invention is better understood, the same consists in the novel construction, combination and arrangement of parts here-

inafter more fully described, illustrated and 55 claimed.

A preferred and practical embodiment of the present invention is illustrated in the accompanying drawings, in which—

Figure 1 is a vertical sectional view of 60 my invention showing the relation of parts during the working stroke.

Fig. 2 is a vertical sectional view showing 65 the relation of parts at the end of the exhaust stroke.

Figs. 3, 4, 5, and 6 are diagrammatic views 70 respectively showing the position of parts at the beginning of the suction stroke; the beginning of the compression stroke; the beginning of the working stroke; and the end 75 of the working stroke.

Similar reference characters designate 80 corresponding parts throughout the several figures of the drawings.

In carrying out the present invention, it 75 is proposed to utilize an automatically reciprocating working cylinder designated generally by the letter C, and combining all of the functions of an engine cylinder and a variable sliding sleeve. This cylinder which 80 will be presently explained operates within a fixed guide casing 1. The said guide casing is preferably of a cylindrical construction, and may be provided with any conventional cooling means such, for instance, 85 as a water jacket 2.

The guide casing 1 is formed with the oppositely arranged inlet passages 3—3' and 90 exhaust passages 4—4'. These passages having the ports a and b are shown in paired 95 relation, but it will be understood that they may also be of any number even or odd, and may extend entirely around the casing. It is, of course, understood that a carburetor is connected to the passage 3—3' and an exhaust pipe to 4—4'. Furthermore, the said 100 casing is formed with a housing casing 5 for accommodating the working parts of the engine, and the cylindrical bore 6 of the casing receives the reciprocating working cylinder C. The body of this working cylinder is preferably in the form of a long sleeve 7 operatively related to a cylinder operating mechanism designated generally as 8, and hereinafter more particularly referred to.

The working cylinder C carries at its upper end a head section 9 having a piston fit

in the casing and provided with a plurality of piston rings 9^a to establish and maintain this fit. Also, the said head section includes the closed cylinder head 10 having a spark plug opening 11, and on the exterior of the head section adjacent the cylinder head 10, the same has formed therein an annular groove 12 adapted to register with the ports *a* and *b* in the casing, and also in permanent communication with the combined feed and exhaust ports 13 which pierce the wall 7 of the cylinder immediately beneath the cylinder head 10. As noted, this annular groove 12 is adapted to alternately register with the inlet ports *a* and the exhaust *b* respectively of the inlet passages 3 and 3' and exhaust passages 4 and 4', to thus alternately admit and discharge the live and dead or inert gases from the interior of the chamber 20 or space *c* of the sleeve 7.

Operating within the working cylinder C is a piston 14 which actuates the crank shaft 15 by means of the usual connecting rod 16, and as will be apparent from the drawings, this piston 14 and sleeve 7 are so timed in their operations that at the end of the exhaust stroke, the upper end of the piston registers with the lowest point of the openings 13, so that practically all of the dead or inert gases may be expelled from the chamber *c* into the exhaust passages 4 and 4'. This feature will hereinafter more fully appear in connection with the operation of the invention.

Another novel and distinctive feature of the present invention resides in the means employed for imparting a reciprocating motion to the working cylinder C. Although this may be accomplished in various ways, a preferred and practical method to this end involves the novel structure more clearly shown in Fig. 1 of the drawings, which operates accurately and positively, and permits of ready adjustment whereby the movement of the sleeve may be easily synchronized with the movement of the piston. Referring to this construction, it will be observed that the sleeve portion 7 of the cylinder is provided near its lower end with a pair of diametrically opposite projections preferably in the form of cam rollers 17, which are mounted on axle pins 18 rigidly fixed in the cylinder wall, and are preferably provided with ball bearings 19 to insure the reduction of friction to a minimum and thereby increase the efficiency of operation.

These cam rollers 17 are adapted to work in a sinuous cam groove 20 formed in a rotary valve operating gear ring 21 rotatably supported as indicated at 21^a in the casing 5 and surrounding the base of the sleeve 7. This gear 21 is for the sake of convenience in assembling, formed in two sections 65 designated as 22 and 23, and carries on its

outer periphery a circular worm rack 24 which meshes with a worm 25 on a worm shaft 26 suitably journaled in the casing 5 of the engine. It will, of course, be understood that, although only one cylinder is shown in the present illustration, the shaft 26 may be common to a plurality of cylinders. As will be apparent from Fig. 1, the gear ring 21 has formed on its lower face a pair of oppositely located depending impact lugs 26^a, which are adapted to receive the impact of the outturned impact flanges 27 carried by the bottom of the sleeve 7. These lugs 26 only extend part way around the gear 21, as do likewise the flanges 27, and are so spaced that during the compression and working strokes they come in contact to resist the impact, and take the wear and strain off the cam rollers 17.

In order to hold the working cylinder C in a relatively fixed position, or in other words to prevent its rotation, and thus insure a positive reciprocating motion to be imparted thereto by the rollers 17 working in the groove 20, the lower end of the sleeve 7 is provided with an offset or laterally extending holding yoke 28 which engages a relatively fixed valve shifting eccentric 29 carried by an eccentric shaft 30, preferably arranged in a vertical position at one side of the lower part of the sleeve, and provided at its upper end with an operating arm 31. Thus, as the working cylinder C is engaged with the relatively fixed eccentric 29, it is prevented from having any rotary movement, but is free to reciprocate and thus carry out its functions with respect to the piston and casing.

Normally, the eccentric 29 is adapted to hold the cylinder C in such a position that the rollers 17 will rest in the groove 20 so that the operation of the gear 21 will always bring the cylinder head 10 of the cylinder in proper relation to the upper end of the piston 14, to thereby clear the compression space *c* of all dead or inert gases during the operation of the engine at normal speeds. However, when the engine is running at higher speeds, it is desirable that the compression chamber *c* be cleared of the dead or inert gases much more rapidly than under usual conditions. Therefore, to advance the valve action with relation to the movement of the piston and crank shaft while the engine is running so as to counteract as much as possible the inertia of the gases, the eccentric 29 may be turned through the operating rod 31 to turn or alter the position of the working cylinder. This turn brings the rollers 17 from the position which they normally occupy in the groove 20 to a point nearer the sharp turn or angle in the cam groove whereby the head 10 of the sleeve will be brought to its exhaust position much quicker than under ordinary circumstances.

so that the intake ports will be opened earlier, allowing a full charge to enter, and the exhaust ports will open sooner to allow complete scavenging.

- 5 The several positions that the valve sleeve 7 is caused to assume by the means just described are clearly shown in the drawings. In Fig. 2 which shows the end of the exhaust stroke, the working cylinder C is in its 10 lowermost position so that the groove 12 registers with the ports b of the exhaust passages 4 and 4'. While the piston 14 remains in the same position shown in Fig. 2, at the end of the exhaust stroke at upper 15 dead center, the cam gear 21 through the groove 20 and rollers 17 quickly moves the sleeve upwardly so that the groove 12 of the sleeve registers with the ports a of the inlet passages 3 and 3' to thus begin the 20 suction stroke as shown in Fig. 3. The piston 14 then recedes, and when the end of the suction stroke is reached, the cam devices cause the cylinder C to be lowered so that the groove 12 is approximately midway between the ports a and b at the beginning of the 25 compression stroke, as shown in Fig. 4. Near the end of the compression stroke, the charge is fired, thus causing the piston 14 to begin its working stroke as shown in Fig. 30 5. During this working stroke the cylinder C is in such a position that the groove 12 is out of registry with the exhaust ports b. However, when the end of the working stroke is reached as shown in Fig. 6, the groove 12 registers with exhaust ports b.

From the foregoing, it will be apparent that the cylinder C is positively and accurately synchronized with the movement of the piston 14 to accomplish the several steps 40 in the cycle of operation, whereby the compression chamber c is varied to alternately receive a full live charge, and then completely expel the inert or spent gases and thereby not impair the efficiency of the next 45 succeeding charge.

Without further description, it is thought that the many features and advantages of the present invention will be readily apparent, and it will also be understood that various changes in the form, proportion, and minor details of construction may be resorted to without departing from the spirit of the invention or scope of the appended 50 claims.

55 I claim:

1. An internal combustion engine including a casing having inlet and exhaust ports, a sliding working cylinder having a common intake and exhaust port for alternately registering with said casing ports, a piston sliding in said working cylinder, cam means for moving said working cylinder, and means for advancing the action of the working cylinder with relation to the crank shaft while the engine is running.

2. An internal combustion engine including a casing having inlet and exhaust ports, a sliding working cylinder having a common intake and exhaust port for alternately registering with said casing ports, said working cylinder port being formed by a groove around the periphery of the cylinder, and a plurality of radially disposed openings establishing communication between the groove and the interior of the cylinder, a piston working in said cylinder, and means for reciprocating said cylinder in synchronism with the piston.

3. An internal combustion engine including a casing having inlet and exhaust ports, a working cylinder having a piston head provided with a common intake and exhaust port formed by an annular groove and a plurality of radially disposed openings, said common intake and exhaust port being adapted to alternately register with the casing ports, a piston working within said cylinder, and cam means for actuating said cylinder in synchronism with the piston.

4. An internal combustion engine including a casing having inlet and exhaust ports arranged at different levels, a sliding working cylinder located within the casing and having a combined intake and exhaust port for alternately registering directly with said casing ports, said cylinder having offset flanges at one end, relatively fixed projections carried by said cylinder, and cam means for engaging said projections to operate the cylinder, said cam means having spaced depending lugs arranged to contact with said offset flanges on the cylinder during the compression and working strokes of the engine.

5. An internal combustion engine including a casing having inlet and exhaust ports, a sliding working cylinder located within the casing and having a common intake and exhaust port for alternately registering with said casing ports, relatively fixed projections carried by said cylinder, and cam means for engaging said projections to operate said cylinder in synchronism with the piston, said cam means comprising a sectional gear ring having a cam groove and also having a worm rack and rotatably supported on the cylinder, and a worm for operating said gear ring through the worm rack.

6. An internal combustion engine including a casing having inlet and exhaust ports, a sliding working cylinder located within the casing and having a common intake and exhaust port for alternately registering with said casing ports, relatively fixed projections carried by said cylinder, and cam means for engaging said projections to operate said cylinder in synchronism with the piston, said cam means comprising a gear ring having oppositely depending lugs on its bot-

tom face and also having a cam groove, a rack carried by said ring, a worm meshing with said rack, and laterally projecting flanges carried by said cylinder for abutting 5 with said depending lugs on the gear ring.

7. An internal combustion engine including a casing having inlet and exhaust ports, a sliding working cylinder having a common intake and exhaust port for alternately 10 registering with said casing ports, projections carried by the cylinder, impact flanges also carried by the lower end of the cylinder, and means for operating said cylinder including a gear ring having a cam groove 15 for engaging said projections carried by the cylinder, a worm for operating said gear ring, and impact lugs carried by the gear ring for abutting with the impact flanges on the cylinder on the compression and 20 working strokes of the piston.

8. An internal combustion engine includ-

ing a casing having separate oppositely located inlet and exhaust ports located at different levels, a reciprocating working cylinder operating within said casing and having a single combined inlet and exhaust port for alternately registering direct with said casing ports, a piston working within the cylinder, cam means for reciprocating said working cylinder, and adjustable means 25 engaging with said cylinder whereby the same may be guided in its reciprocating movement and shifted to advance and retard the same with relation to said cam means in proportion to the speed of the engine. 30

In testimony whereof I hereunto affix my signature in the presence of two witnesses.

JOHN FRANCIS MURPHY.
